CLOSURE MEANS FOR FLEXIBLE-WALLED CONTAINERS

Karl E. Freund, Los Angeles, Calif., and Elmer M. Scharenberg, Cuyahoga Falls, Ohio, assignors to The B. F. Goodrich Company, New York, N. Y., a corporation of New York

Application May 14, 1946, Serial No. 669,652

1 Claim. (Cl. 150—3)

This invention relates to flexible wall structures and closure means therefor, and pertains more specifically to fluid containers with a flexible wall structure having an elongated access opening and closure means for said opening.

One object of the invention is to provide a flexible wall structure with a narrow, elongated opening and a light-weight closure means, positive in action.

Another object of the invention is to provide a fluid container having flexible walls with a narrow, slot-like opening which may readily be enlarged or distorted to provide access to the interior of the container and a closure for the opening which may readily be inserted and removed.

Another object is to reduce to a minimum the weight of flexible fuel tanks adapted to contain hydrocarbon liquids for use in motor vehicles such as automobiles, motorboats or airplanes, and still provide a large access opening in the wall of the flexible tank to permit convenient inspection and repair of the interior of the tank.

Another object is to provide an arcuate or angular elongated opening in the wall of a flexible fuel tank, and a light-weight, readily removable closure means therefor, so that the flap-like portion of the wall inside the arc or angle may readily be folded back to afford access to the interior of the tank, and to provide facility in manufacture and convenience in operation.

These and other objects of the invention will be apparent from the description which follows.

In the appended drawings,

Fig. 1 is a view in perspective of a flexible-walled fluid container provided with three embodiments of the device of this invention with one set of cover plates partly broken away and in section;

Fig. 2 is a view in section along line 2—2 of Fig. 1;

Fig. 3 is a view in section along line 3—3 of Fig. 1, and

Fig. 4 is a view in section along line 4—4 of Fig. 1.

In Figs. 1 and 2, the flexible wall structure 10 comprises one or more layers of textile fabric, paper, or the like, coated or impregnated with synthetic resinous or rubbery material. If the container is to be used for hydrocarbon liquids, such as gasoline or oil, the coating or impregnating material is preferably one which is unaffected by such liquids, for example polychloroprene, butadiene-acrylonitrile synthetic rubber, or the like. Additional thin flexible barrier layers of other materials such as superpolyamides may also be

present to reduce diffusion of the liquid through the walls to a minimum.

In a wall of the tank is an elongated slot-like access opening 11 having bead 12 around its margin. The bead may be formed from rubber-like material by a molding or extrusion process and secured to wall 10 by any suitable means such as cement or by vulcanizing the parts together under pressure, or the like, or other suitable flexible bead construction may be provided. The opening 11 is sealed by means of a pair of cover plates 13 and 14 having trough-like grooves 15 at their margins which fit around bead 12. The cover plates are clamped together by means of lock nut 16a and bolt 16 secured to inner plate 13 and extending through the opening 11 and outer plate 14. In this embodiment the outer lips 17 of the cover plates are designed to be more widely separated than the interior portions of the plates to prevent excessive pressure on the rubber-like material used to make the bead. In this construction the central portion of each plate around the bolt acts as a limit stop to prevent the outer lips 17 from bearing too heavily on the bead when the plates are clamped together.

In another embodiment of the invention the elongated opening in the wall of the tank as well as the cover plates 20 and 21 are arcuate in form, as shown in Fig. 1. In this construction the flap-like portion 22 of the wall structure inside the arc may be folded down, after removal of the cover plates, along a line extending between the ends of the opening. In addition, the central portions of cover plates 20 and 21 between the marginal bead-receiving grooves are recessed as shown in Fig. 3 so as to nest together and provide a countersunk construction. The clamping means used in this construction is a closed-end internally threaded tubular rivet 23 having a flange 24 countersunk in the upper surface of plate 21 and at the other surface an upset portion 25 produced by axial compression of the rivet. Screw 26 extending through plate 20 is threaded into rivet 23 and serves to draw the plates together in sealing relationship, with the bead around the margin of the wall opening clamped between the margins of the plates.

In order further to reduce the weight of the closure, the central portion of one of the plates 50 may be cut away except at the points at which it is clamped to the other plate, as shown at 30 in Fig. 1 and in Fig. 4. In this embodiment the inner plate 31 is made continuous to prevent leakage of the fluid through the opening.

In applying the closure of this invention to the

opening the inner plate is first slipped end-wise through the opening and held in place manually while one end of the outer plate is loosely clamped to it. The free end of the outer plate is then swung into position and one or more of the intermediate bolts and nuts are loosely threaded together. After all of the bolts and nuts have been loosely threaded, they may be tightened as desired.

In removing the closure, the reverse procedure may be followed. The opening may then be enlarged by spreading the sides apart near the center, or by turning back flap 22. In this manner a very large opening may be provided with a minimum of added weight for the closure.

Although the precise shape of the opening in the wall structure is not critical, as is apparent from the description above, it should be elongated, preferably slot-like in nature. The ends of the opening are preferably rounded, as shown in Fig. 1, to provide a continuous bead without sharp angles for best sealing.

It will be seen that the device of this invention provides a positive-acting closure which can easily and quickly be put in place or removed.

Although specific embodiments of the invention have been herein described, it is not intended that the invention be limited solely thereto, but that it include all the obvious variations and modifications falling within the spirit and scope of the appended claim.

We claim:

A closure for a liquid container having a flexible wall structure with an access opening therein, said closure comprising a flexible compressible bead secured to said wall structure along the marginal extent of said opening, a relatively rigid plate member at one face of said wall structure extending across said opening, a relatively rigid compression member at the opposite face of said wall

structure in opposing relationship to said plate member, each of said members having a groove along its periphery at the side adjacent said wall structure, and clamping means extending through said opening for pressing said members toward each other with said bead compressed in said grooves along the extent thereof to seal said opening, said clamping means comprising a closed-end internally threaded tubular rivet having a flange portion at the face of said plate member adjacent said opposing member and a shank portion upset by axial compression at the opposite face of said plate member, and a screw extending through said opposing member and said opening and having its shank threaded into said tubular rivet.
